UNITED STATES PATENT OFFICE.

MAXIMILIAN J. OTTO, OF NEW YORK, N. Y.

GAS-JET HEATER.

1,366,886.

Specification of Letters Patent. Patented Jan. 25, 1921.

Application filed January 17, 1920. Serial No. 352,206.

To all whom it may concern:

Be it known that I, MAXIMILIAN J. OTTO, a citizen of the United States, residing in the borough of Manhattan, city, county, and 5 State of New York, have invented new and useful Improvements in Gas-Jet Heaters, of which the following is a description.

This invention has reference to heating apparatus and, particularly, relates to devices or apparatus applicable to fixtures, 10 brackets, or arms for supplying gas light, or applicable to gas burners of any type.

Among the objects of my invention may be noted the following: to provide a gas jet apparatus with means by which the temperature 15 of the surrounding atmosphere, in a room for example, may be raised through a medium applied to the ordinary fixture for gas lighting purposes; to provide a heating apparatus which may be applied to gas burners, fixtures, etc., of any kind or description, either in combination with the lighting 20 means or to the exclusion thereof, for the purpose of furnishing heat to the surrounding atmosphere; to provide a simple, light, inexpensive heating device applicable to gas jet fixtures for the purpose of providing a sufficient degree of warmth or heat in rooms where there is no heating apparatus or 25 where the heating apparatus is inadequate for the purpose; to provide simple, economical, strong and durable means for heating rooms by gas and for applying the same to the ordinary gas fixtures or brackets, or to 30 a specially constructed support or bracket which is portable and may be set upon a table or similar support or upon the floor or otherwise.

With the foregoing objects in view and 40 others which will be detailed during the course of this description, my invention consists in the parts, features, elements and combinations thereof hereinafter described and claimed.

In order that my invention may be clearly understood, I have provided drawings 45 wherein:

Figure 1 is a view in elevation showing heating apparatus adapted to be applied to 50 any gas fixture or other support similar thereto;

Fig. 2 is a vertical section on line 2—2, Fig. 1 of the apparatus;

Fig. 3 is a perspective view of the heating 55 drum of my apparatus shown detached from the latter;

Fig. 4 is a view in elevation showing my heating apparatus applied to the ordinary single arm lighting fixture;

Fig. 5 is a top plan view showing my apparatus applied to a bracket or fixture in combination with lighting means; and

Fig. 6 is a view in elevation showing the same combination of means as in Fig. 5 applied to a portable support adapted to be 65 connected to a gas source.

Referring to the drawings, the numeral 1 indicates the cylindrical body of my apparatus, the same being open at its opposite ends, and provided near its lower end with 70 a large aperture 2 through which the gas at the burner 3 may be lighted. The burner 3 is conventional in form and may be of any known desired or preferable make. Specifically, it forms no part of my invention. 75 The cylindrical body 1, near its lower end, is also provided with a plurality of apertures 4 encircling the body and adapted to supply a sufficient amount of air for combustion purposes, in combination with the 80 apertures 5 in the conical supporting shell 6 rigidly secured in any suitable manner at 7 to the tubular stem 8 of the burner 3, the said stem 8 having an aperture 9 which also furnished air to aid in combustion of the gas. 85 The conical shell 6 is, at its upper open end, provided with an inturned, substantially U-shaped flange 10, which receives within its opening the outturned flange 11 of a ring member 12 removably secured within the 90 base of the cylinder below the encircling row of apertures 4. Thus the cylindrical body is supported removably upon the ring 12, which ring in turn is supported by the shell 6, and the latter in turn supported by the 95 stem 8 of the burner, said stem extending below the shell 6 a sufficient distance to provide a fixture for application to the usual burner-valve 13 carried by the usual bracket or arm 14 fixed to the usual source of supply. 100

The shell 6 is also secured to, and braced by, the stem 8 of the burner by means of a diaphragm 15, through the center of which the stem 8 passes, and which diaphragm, at its circumference, is provided with an upwardly turned flange 16 the angle of which corresponds with the inclination of the shell 6, and to which latter the diaphragm is securely fastened by means of screw 17 and nuts 18. Thus the shell is not only strengthened or stiffened bodily; but, is firmly secured in place upon the stem of the burner. 110

This affords a very firm support for the heating apparatus as a whole, which latter as before noted, is removably secured to the said support, the engagement between the 5 ring 12 and the cylinder 1 being frictional, tight and steady. By making the cylinder and its supported parts removable, as noted the drum supported in the cylinder can be removed when necessary for repairs or re-
10 placement.

The drum mounted within the cylinder is shown as composed,—Figs. 2 and 3,—of two end members or disks 19 and 20, each provided with a plurality of apertures 21 15 in one or more groups, as may be desired or found necessary, said disks being connected together by the perforated cylindrical tubes 22 which, at their opposite ends, are provided with a plurality of lugs 23 turned over and secured upon both surfaces of the disks, this means affording a ready and satisfactory way of securing the heating or radiating tubes to the disks 19 and 20. The heating drum thus composed is suspended 20 within the inclosing cylinder 1 by means of bent arms or brackets 24 secured by vertical intermediate portions to the upper end of the cylinder 1 by means of screws 25 and nuts 26. The arms, at their lower ends, are 25 each bent inwardly to provide a horizontal support 27 on which the disk 19 is set and to which said disk is secured by means of screws 28 and nuts 29. Thus, with a plurality of supporting brackets or arms, such 30 as 24, the drum is rigidly mounted within the cylinder 1, clear of the walls thereof, a space being provided between the disks 19 and 20 and the cylinder 1 for the passage of heat from the chamber 30 between the 35 burner 3 and the disk 20, in which chamber the burner 3 is located. Between the heating tubes 22 and the wall of the cylinder another chamber is provided, and between the upper disk 19 and the heating tubes and 40 the upper end of the apparatus still another chamber is provided, as presently described. The brackets or arms 24 are outwardly bent so as to extend a considerable distance beyond the cylinder 1 and then are inturned, 45 as at 31, to provide a U-shaped flange or support for the flanged open end 32 of the conical dome 33 of the apparatus. Bracket arms 24 rigidly support the dome 33 in position directly above the cylinder 1 and separated from the latter by a sufficient space to allow of the escape of the heat into the surrounding atmosphere. Preferably, the dome 33, at its lower end, is considerably greater in diameter than the cylinder 1, 50 providing thereby a very effective deflector for the heat and enabling the said dome to thereby carry the heat outwardly a considerable distance from the cylinder 1 into the surrounding atmosphere. The dome 33 thus 55 provides an extensive chamber above the

disk 19 and the heating drum; and said dome is provided with a plurality of apertures 34 suitably arranged for the escape of heat from within the said chamber directly into the surrounding atmosphere. At its 60 upper end, the dome is provided with a central aperture surrounded by a short in-turned flange 35, upon which rests a ferrule or sleeve 36 surrounding a screw bolt 37, which extends through the aperture in the 65 dome 33 and is securely held by a nut 38 on the threaded end of the bolt. A cap plate 39 conical in form is mounted upon the ferrule 36 and has the stem of the bolt 37 passing therethrough. Thus, the head 70 of the bolt tightly secures the cap plate 39 upon the ferrule 36 and the support of the said cap plate upon the dome 33 is quite rigid. The function of the cap plate is to prevent the heat rising from the dome, or 75 any products of combustion passing through the dome, reaching the ceiling. Thus the possibility of blackening or soiling the ceiling is eliminated. The cap also has the function of deflecting the heat rising 80 through the dome downwardly and outwardly into the surrounding atmosphere.

The heating apparatus produced as thus described may be, as shown in Fig. 4, mounted upon the fixture 14, which is the 85 usual gas bracket arm, after removing the lighting tip therefrom. If it is desired to obtain light and heat simultaneously, the entire burner and tip can be removed from the valve member 13 of the bracket arm and 90 in its place a fixture can be applied as shown in Figs. 5 and 6, the fixture in this instance being a T-shaped member 40, the stem of 95 which is applied to the valve member 13 of the bracket arm 14, and the head of which has extending therefrom in opposite directions the pipes or arms 41 and 42, the arm 41 having my heating apparatus applied thereto, as shown in Fig. 4, and the arm 42 having the usual gas cock and burner indicated generally by 43 applied thereto. Thus, heat and light can be furnished at 100 the same time through a single fixture 14 having applied thereto the attachment 105 40—42; and heat or light may be obtained as desired. Instead of supporting my heating apparatus upon a fixed arm or bracket such as 14, it may be applied to a heavy 110 portable base 44, as shown in Fig. 6, the same consisting of a weighted or very heavy circular or other shaped member adapted to rest on a table, the floor or otherwise, and having extended centrally therefrom a stem 45 connected with a fixed pipe 46, in turn coupled in suitable manner to a flexible 115 pipe 47 secured to the source of supply. The stem 45 of the base or support 44 has the heating and lighting fixture shown in Fig. 5 applied thereto in the same manner as it is applied to the bracket arm 14. Thus 120 125 130

a lighting and heating device portable in character can be set upon a table, in a room or otherwise, to provide either or both heat and light in manner similar to a drop light, 5 student's lamp, etc.

From the foregoing it will be seen that I have produced a very simple and effective heating apparatus which is adaptable to the ordinary gas jet or bracket arm as a substitute for the light burner, or which can be so applied to a supporting member or device as to afford both light and heat simultaneously. It will also be seen that my heating device will supply a very great amount 10 of warmth, and, when it is thoroughly heated, will radiate heat quite extensively into the surrounding atmosphere and afford a sufficient heating medium even in very cold weather.

Having thus described my invention, what I claim and desire to secure by Letters Patent is:

1. A gas jet heater comprising a cylindrical body; a heating drum and means for suspending the same within the body; means at the bottom of the heater for supporting

the same upon a gas fixture; a dome mounted upon the body; and a cap mounted centrally upon the dome with its circumference free to prevent products of combustion from 30 rising.

2. A gas jet heater comprising a body portion; a perforated base entirely closing the body portion; a burner mounted centrally in the base and having an extended 35 stem for supporting the heater upon a gas fixture; a drum consisting of a plurality of perforated tubes joined at opposite ends by disks; and means for suspending said drum within the body portion out of contact with 40 the latter and above the burner.

3. In combination with a support through which a supply of gas may be obtained; a fixture applied thereto; a source of light secured to one end of the fixture; and a 45 source of heat secured to the other end of the fixture; said source of heat comprising a supporting base; a cylindrical heat radiating body; a heating drum within said body; a dome mounted on said body; and a 50 cap mounted upon the dome.

MAXIMILIAN J. OTTO.
